UNITED STATES PATENT OFFICE.

LOUIS OSTROW, OF NEW YORK, N. Y.

PUBLISHER'S MECHANICAL LAY-OUT AND BULLETIN APPARATUS AND METHOD.

1,261,847.

Specification of Letters Patent.

Patented Apr. 9, 1918.

Application filed November 23, 1916. Serial No. 133,044.

To all whom it may concern:

Be it known that I, LOUIS OSTROW, a citizen of the United States, residing at New York, in the county of New York and State of New York, have invented certain new and useful Improvements in Publishers' Mechanical Lay-Out and Bulletin Apparatus and Methods, of which the following is a specification.

10 This invention has to do with the art of printing, and comprises an improved publishers' mechanical layout and bulletin apparatus and method of using the same.

While the method and apparatus of this 15 invention are particularly designed with a view to being employed in publication and printing offices where it is required to periodically set up advertising forms, known ordinarily as classified advertising forms, 20 where numerous small advertisements, which may be termed broadly "printed sections" are required to be printed, I do not wish to be limited to the above particular adaptation of the invention. As a matter of fact, 25 the method and apparatus hereinafter to be set forth in detail are especially advantageous for use in connection with the making up and laying out of pages of type matter to be printed whenever said pages are 30 comprised of many relatively small printed sections such as might correspond to classified advertisements, but which may in fact have an entirely different character.

Speaking now with reference to the particular use of my invention as previously 35 mentioned, it may be noted that the classified advertising pages of publications present peculiar difficulties by way of an unusual amount of detail work incidental to the making up and laying out of the great number 40 of printed sections or advertisements constituting such pages. Different factors make for an endless amount of such detail work preliminary to closing the forms of classified 45 advertising, or equivalent printed pages, and involve such matters as the necessity of frequent changes in the subject-matter of each advertisement or printed sections, the requirements that advertisements under different 50 classifications be omitted or reinserted, and the constant need for a manager in charge of the make-up and fulfilment work to know how much space in the form has been taken, to enable matter to be prepared 55 and supplied for vacant space, and other

difficulties of the same sort. On top of the foregoing it should be borne in mind that it is customary for publications to close their forms at a certain time, and hence notwithstanding the constant changes occurring to 60 affect the size and arrangement of the advertisements or sections of the final printed page, it is prerequisite to be able to determine upon the final make-up and layout of the printed page with the utmost promptness when the closing of the forms for the 65 press is ordered.

The improvements of my invention are intended to provide an apparatus susceptible of constant use in the publication or 70 printing office, in the department ordinarily known as the make-up and fulfilment department, by which apparatus a very large portion of the detail work now constantly required in all publication offices as a preliminary to the closing of forms for printed 75 pages of the character above set forth, is avoided, the said apparatus being employed in accordance with a method which I have devised involving certain steps required to 80 be performed in a regular and predetermined order and which afford a remarkable saving of time and extraordinary convenience to those in charge of the make-up and fulfilment work described.

While the present invention is intended to supply an apparatus and method facilitating to a high degree the make-up and fulfilment work of publication departments, 90 along the lines above premised and having to do particularly with the final arrangement of the type of the advertising forms, my invention has utility of a somewhat different nature owing to the fact that the apparatus employed by me is virtually a lay-out bulletin adapted to be used as a bulletin *per se* to keep those in charge of make-up work advised from the start to the finish of such work as to conditions surrounding the 95 number, size, character and other features of the numerous printed sections or advertisements that will ultimately make up the printed page to be finally published. That is to say, as the printed sections or advertisements are received in the make-up department my apparatus is intended to afford an accurate register or bulletin showing the space to be taken, position to be occupied, and the character of all the particular printed sections or advertisements received and 100

105

110

111

intended to go into the form by which the final page or pages will be printed.

In the accompanying drawings:—

Figure 1 is a plan view of an apparatus embodying the essential features of the present invention and illustrative of only one form which the apparatus may take in order that the method also constituting this invention may be practised;

10 Fig. 2 is a cross sectional view through the layout form on the line 2—2 of Fig. 1;

Fig. 3 is a sectional view on the line 3—3 of Fig. 1, showing more particularly the construction of one of the resilient pressure devices coacting with the base members;

15 Fig. 4 is a fragmentary view somewhat enlarged to bring out the manner in which my apparatus is used, advertising cards or printed sections being actually applied to the 20 movable base members disposed in the frame of the layout form;

Fig. 5 is a somewhat diagrammatic view showing a casing adapted to hold base members or blocks of different sizes such as may 25 be necessary to be used in publication offices for the purpose of receiving advertisements or equivalent printed sections of a different character and of different sizes as regards 30 number of lines to be used and width of column; and

Figs. 6 and 7 are fragmentary sectional views showing more fully the clamping means coöperating with one of the plungers.

To enable the fullest comprehension of 35 the utility of the apparatus and method of this invention a recapitulation of the ordinary practices employed in make-up and fulfilment departments of publications may here be given.

40 Assuming that we are dealing with the printing of the classified advertisements of a publication, the customary steps involved in printing the advertisement on the final printed page from the time of receipt of the 45 advertisement may be briefly summarized as follows:

First—The copy for the advertisement is received from the advertiser.

Second—The copy for the advertisement 50 is delivered to the make-up man in the make-up and fulfilment department.

Third—After a proper record of the advertisement is made it is sent to the printer along with many other advertisements, is 55 set up in galley form and a galley proof returned to the make-up department.

Fourth—At this time changes in the copy which may be instructed by the advertisers from whom the advertisements have been 60 procured are made on the galley proof. These changes may involve the shifting of ads from one classified heading to another when advertisers change their minds at the last moment, the giving of a better place in 65 a column under a classification to advertisers

who may not have obtained results, or for whom better results are desired to be secured.

Fifth—The next step is the return of the changed proof to the printer along with 70 what is usually called a guide, consisting of a set of rather complicated directions explaining the changes made. It is very difficult often for the printer to follow the guide to the extent of making the corrections accurately but this is done as best possible and revised galley proofs are sent to the make-up man along with layout sheets.

Sixth—With the revised galley proofs in hand, together with the make-up sheets, the 80 columns of advertisements under the classifications are laid out on the make-up sheets, the manager usually being consulted to get an idea of the space he wishes to use for his purposes, when spaces are to be left on 85 the pages. For this purpose accurate counting of the lines of advertising is necessary to insure that the space above mentioned, usually called form space, will be left, and owing to the human factor involved errors 90 frequently arise in this counting or estimating work.

Seventh—The layout, however, completed, with the galley proofs divided up 95 and applied to the make-up sheets, the latter go back to the printer and the type is laid out in the form in accordance therewith, a page proof struck off, and when this is O. K'd the type usually go to the foundry 100 for casting of the form for the press.

Having in view the various customary steps employed in the practice of making up the printing forms as above described, reference may now be made to the drawings in connection with which I will describe the 105 apparatus of my invention.

In the drawings, A denotes a frame which is preferably made of a size conforming with the size of the page or pages of the publication which is to be printed, and the classification of the printed sections or advertisements of which is ordinarily the work of the make-up department. The frame A may be of any simple construction and is preferably divided into columns by the vertical partitions B, the opposite ends of each of which are seated in recesses C in the upper and lower ends of the frame. Adjacent to the recesses C the ends of the frame A may be cut out to form thumb spaces, this however not being absolutely essential as a feature of construction of the invention.

Disposed between the sides of the frame A and the partitions B, and therefore arranged practically in columns, are a plurality of base members or blocks D. The blocks D are of the same size as the space to be occupied by advertisements which are to be set up in type to form a part of the final printing form. Certain of the base mem- 130

bers D likewise are to be of the same size, and occupy the same space therefore, as the headings which divide the various classifications such as are customarily employed 5 for printing pages of classified advertisements.

There are provided in the frame A also, which frame, it should be stated, has a suitable bottom or back E, a series of spacers 1.

10 The spacers 1 may be set to correspond with leads or rules that are provided ordinarily between the different printed sections constituting the advertisements as referred to herein. While in Fig. 1 the spacers 1 are disposed 15 intermediate all of the various base members D, it should be borne in mind that in the actual use of the apparatus said spacers may be inserted between the parts D at any convenient time during the use of the apparatus.

20 It is contemplated that the members D shall be freely movable in the column spaces in which they are mounted so that the members may be readily withdrawn or shifted to different points of location either in the 25 particular column in which they may already be, or in other columns such as established by the sides of the frame A and the partitions B. On the other hand, it is desirable that the said base members D shall 30 not be liable to accidental displacement, for which reason I provide at the top of each column space of the frame A a yieldable plunger 2, said plunger being adapted to bear against the uppermost member D in 35 the particular column. Since the plunger 2 is acted upon by a spring 3 partially housed within the plunger and within a casing 4 applied to the upper end of the frame A, the plunger is adapted to exert a resilient 40 pressure against all of the members D in the column adjacent to which the member 2 is disposed. There is provided a screw connecting the plunger 2 with the casing 4 and by the removal of this screw, adjustment 45 or replacement of the plunger spring 3 or other parts may be effected. The casing 4 is preferably integral with a plate 5 secured by screws to the upper end bar of the frame A.

50 Having in view the construction of the apparatus as above described, which apparatus may be appropriately called a layout form, the method adapted to be practised in connection with this apparatus, whereby to 55 simplify the whole system of printing numerous printed sections going to make up a printed page, or small advertisements, if said sections happen to be advertisements, is substantially as follows:

60 On receiving the advertisements, assuming that the printing of the page is just being started, the advertising copy is brought to the make-up department and the usual record is made. The copy is then sent to the 65 printer with the copy for other advertise-

ments and a galley proof struck off and returned to the make-up man. If desired, as the advertisements are received, and assuming that certain of the base members D have been marked with classification heads such 70 as illustrated in Fig. 3, the make-up man may readily apply indicia to the base members 1 representative of the advertisements received and which have been sent to the printer for galley proof. 75

In the apparatus shown, all of the base members D are of the same size, said apparatus being intended for use in connection with a printed page of advertisements or printed sections of like size. Thus it will be 80 apparent that as the advertisements are received the make-up man may immediately start the laying out or the making up of his advertising page by arranging a base member B corresponding to the advertisement in 85 the column and under the classification it is intended to go. When the galley proofs of the advertisements come from the printer they may be cut up and pasted or otherwise applied to the base members D. Thus as the 90 advertisements for the printed page for which the layout form of the apparatus is used, come in or accumulate they may be actually laid out in the positions which they will occupy in the final type form, or at 95 least in approximately the positions they will occupy, a particular object of the invention being to obtain such a flexibility of system as to enable the make-up man to quickly shift the base members D and the 100 advertisements or printed sections represented thereby so as to have the layout form complete at all times up to the time of arrival of the last received advertisement.

105 Thus it is that considerable time consumed in obtaining galley proofs from the printer, making changes on said proofs, and returning to the printer for subsequent proofs, and laying out the proofs on layout or make-up sheets, is entirely avoided in the practice of 110 this invention and a fair estimate of the time consumed in all of the ordinary operations employed today for the purposes of this invention in publication offices makes the suggestion that by the present invention practically two-thirds of the usual time used for the make-up and fulfilment work is saved, a reasonable estimate. 115

120 It is to be understood, supplemental to the foregoing, that once the general layout of the advertisements is attended to in the use of the apparatus comprising the layout form above described, the moment the order to close the forms for the press is received it is only necessary to transfer the layout form of 125 this invention from the make-up and fulfilment department to the printer who will then immediately arrange the set up type in accordance with the layout as disclosed by the apparatus, and this done the type 130

forms will be closed as usual and without delay except for final page proofs.

It will be understood, furthermore, that it is contemplated to use any suitable number of the apparatuses of this invention according to the number of pages comprised by the various printed sections or advertisements, one for each page. Likewise, where it is customary for different sized printed sections or advertisements to be admitted to make-up the final printed page I merely contemplate the use of base members D in the form of blocks of different widths and lengths to correspond with the different number of lines of type space to be employed and the different widths of columns in which the lines of type are to be set. The user of the apparatus may readily select a base member D in correspondence with the particular size of advertisement or printed section to be printed, and under these conditions the layout form will always express, so to speak, the proper condition of the work in progress in the make-up and fulfilment operations.

In the actual practice of my method it will be borne in mind that in respect to many publications made up of pages containing small advertisements or printed sections required to be arranged in a regular order, a large number of the printed sections are repeatedly used. That is to say that in respect to classified advertisements, for instance, quite frequently two-thirds or three-fourths of the advertisements are printed more than once. Under these conditions it will be evident that the layout form with the base members D adjusted in closed form condition for an issue of the publication may be used again and again without necessitating the pasting of the classified advertisement proofs or copy upon the base members D when said copy is repeat copy. Quite frequently, therefore, once the copy is applied to a particular base member D the latter may be used indefinitely so long as the printed section or advertisement represented thereon is not killed or discontinued, speaking in the terms of the trade.

The upper end of the frame A of the apparatus may be equipped with supporting members in the form of eye screws to enable the frame to be hung in a convenient place so as to be consulted as a sort of bulletin in a self evident manner. Should it be desired to positively lock the members D in adjusted positions against accidental or unauthorized displacement, suitable locking means such as adjustable rods or the like quite frequently used in filing devices may be applied to the frame A in such a manner as to be movable into one position to lock all of the members D in a column, or moved into another position whereby to release these members D and permit of their ready manipulation by

way of removal, replacement, adjustment, etc. Ordinarily the resilient pressure exerted on the members D by the plungers 2 will suffice, however, to prevent said accidental displacement. In lieu of locking rods such as above referred to, furthermore, some convenient form of cam device coöperative with each plunger 2 may be provided so that when the apparatus is to be used for bulletin or similar purposes the cam device may be actuated to force the plungers 2 hard against the uppermost or contacting members D in the frame A and thereby exert such a clamping pressure as to prevent the members D from falling out of the frame. Such a cam device is illustrated in Fig. 6, the cam being indicated 6 and engaging with the wall of a notched portion 2' of the plunger 2. The cam has a thumb piece 7 by which it may be shifted in one way to positively cam the plunger against the members D for the purpose above described, while if the cam is moved in an opposite position it is practically inactive as regards the plunger, permitting the latter to operate resiliently by means of the spring 3 previously referred to.

The positions assumed by the various base members D as they are arranged in the use of my invention may be termed "closed form positions" because they are always adjusted by the manipulation of the operator to positions in which they are adjacent to one another and properly spaced and which they would occupy if at the particular moment orders to close forms were received. It is this adaptability of the apparatus for the placement of the various members D and 1 in closed form positions which constitutes a very essential and highly important feature of operation of my invention as regards both said apparatus and the method of its use under practical working conditions.

Having thus described my invention, what I claim as new is:

1. The method of make-up and fulfilment to facilitate closing of forms in printing establishments for printing pages comprising a plurality of separate printed sections in regular order, the same consisting of applying to a plurality of movable base members, as the said sections are received, distinctive indicia representative of said sections, and manipulating the base members to cause them to assume positions relatively the same as the closed form positions of the printed sections, whereby the layout of the printed page may be ascertained at any time prior to going to press.

2. The method of make-up and fulfilment to facilitate closing of forms in printing establishments for printing pages comprising a plurality of separate printed sections in regular order, the same consisting of applying to a plurality of movable base mem-

bers corresponding in sizes to the sizes of the said printed sections, and as the sections are received, distinctive indicia representative of the sections, and manipulating the 5 base members to cause them to assume positions relatively the same as the closed form positions of the printed sections, whereby the layout of the printed page may be ascertained at any time prior to going to press.

10 3. The method of make-up and fulfilment to facilitate closing of forms in printing establishments for printing pages comprising a plurality of separate printed sections in regular order, the same consisting of applying 15 to a plurality of movable base members, as the said sections are received, distinctive indicia representative of said sections, and manipulating the base members to cause them to assume positions relatively the same 20 as the closed form positions of the printed sections to act as a guide for the printer in setting up the type of the sections in proper closed form positions, whereby the layout of the printed page may be ascertained at 25 any time prior to going to press, and arranging the type of the printing form to be used for the printing of said sections in accordance with the indicia carried by said base members when in closed form positions.

30 4. The method of make-up and fulfilment to facilitate closing of forms in printing establishments for printing pages comprising a plurality of separate printed sections in regular order, the same consisting of applying 35 to a plurality of movable base members, as the said sections are received, facsimiles of the printed sections, and manipulating the base members after the said sections are applied to cause them to assume 40 positions relatively the same as the closed form positions of the printed sections, whereby the layout of the printed page may be determined at any time prior to going to press.

45 5. The method of make-up and fulfilment to facilitate closing of forms in printing establishments for printing pages comprising a plurality of separate printed sections in regular order, the same consisting of applying 50 to a plurality of movable base members corresponding in sizes to the sizes of said printed sections, and as the sections are received, actual sized facsimiles of the sections, and manipulating the base members 55 to cause them to assume positions relatively the same as the closed form positions of the printed sections, whereby the layout of the printed page as illustrated by the arrangement of the facsimiles of the sections arranged 60 substantially the same as will be the layout of the printed page comprising said sections, when completed.

65 6. The method of make-up and fulfilment to facilitate closing of forms in printing establishments for printing pages comprising

ing a plurality of separate printed sections in regular order, the same consisting of setting up the type for the printed sections, striking off proofs of the sections from the said type, applying the said proofs separately to a plurality of movable base members so as to constitute distinctive indicia representative of the various printed sections as the latter are to be actually printed, and manipulating the base members to cause them to assume positions relatively the same as the closed form positions of the printed sections, and spacing out the base members so the whole space to be occupied by the printed sections may be determined, so whereby the layout of the printed page may be determined at any time prior to going to press.

7. The method of make-up and fulfilment to facilitate closing of forms in printing 85 establishments for printing pages comprising a plurality of separate printed sections in regular order, the same consisting of setting up the type for the printed sections, striking off proofs of the sections from the 90 said type, applying the said proofs separately to a plurality of movable base members so as to constitute distinctive indicia representative of the various printed sections as the latter are to be actually printed, 95 manipulating the base members to cause them to assume positions relatively the same as the closed form positions of the printed sections, whereby the layout of the printed page may be determined at any time prior 100 to going to press, and arranging the type of the printing form in accordance with the arrangement of the proofs of the sections as applied to said base members.

8. The method of make-up and fulfilment 105 to facilitate closing of forms in printing establishments for printing pages comprising a plurality of separate printed sections in regular order, the same consisting of applying to a plurality of movable base members, as the said sections are received, distinctive indicia representative of said sections, manipulating the base members to cause them to assume positions relatively the same as the closed form positions of the 110 printed sections to act as a guide for the printer in setting up the type of the sections in proper closed form positions, whereby the layout of the printed page may be ascertained at any time prior to going to press, 115 and spacing out and arranging the type of the printing form in accordance with the indicia carried by said base members when in closed form positions.

9. The method of make-up and fulfilment 125 to facilitate closing of forms in printing establishments for printing pages comprising a plurality of separate printed sections in regular order, the same consisting of applying to a plurality of movable base 130

members, as the said sections are received, distinctive indicia representative of said sections, maintaining the base members under resilient pressure to hold the same against 5 accidental displacement, and manipulating the base members while under such pressure to cause them to assume positions relatively the same as the closed form positions of the printed sections, whereby the layout of the 10 printed page may be ascertained at any time prior to going to press.

10. The method of printing pages of type-set matter comprising a plurality of separate and distinct printed sections arranged in 15 regular order, the same consisting in setting up the said sections in type, striking off proofs of the sections from such type, applying each separate proof of the several sections to a movable base member of a size 20 corresponding with that to be occupied by the printed section in the complete printed page, and manipulating the base members into closed form relation to constitute a guide representative of the general layout of 25 the various printed sections as they will appear in the final printed page.

11. The method of printing pages of type-set matter comprising a plurality of separate and distinct printed sections arranged 30 in regular order, the same consisting in setting up the said sections in type, striking off proofs of the sections from such type, applying each separate proof of the several sections to a movable base member of a size 35 corresponding with that to be occupied by the printed section in the complete printed page, manipulating the base members in the closed form relation to constitute a guide and layout form for correspondingly arranging the type sections, and then arranging 40 the type for the various printed sections in positions corresponding with the positions of the proofs on the base members of the layout form.

45 12. The method of make-up and fulfilment to facilitate the closing of printing forms, which consists in applying to a plurality of movable base members of a size corresponding to the size of printed sections of a complete printed page, indicia 50 representative of said printed sections, as

sembling said base members so as to provide a layout form, and manipulating the base members in said layout form so as to cause said members to occupy closed form 55 positions corresponding with the closed form positions of the printed sections when actually printed.

13. The method of make-up and fulfilment to facilitate the closing of printing forms, 60 which consists in applying to a plurality of movable base members of a size corresponding to the size of printed sections of a complete printed page, indicia representative of said printed sections, assembling said base 65 members so as to provide a layout form, manipulating the base members in said layout form so as to cause said members to occupy closed form positions corresponding with the closed form positions of the printed 70 sections when actually printed, and then arranging the type for the printing of said printing sections in a manner corresponding with the arrangement of the corresponding representative indicia of the layout form. 75

14. In apparatus of the class described, a layout form comprising a frame, a series of partitions removably fitted into opposite ends of the frame and extending along the frame in such a manner as to divide the latter into a series of column-like spaces, a series of movable base members disposed in said spaces and of a number sufficient to fill the free portions of said spaces, plungers mounted upon an end of the frame, each 85 plunger being adapted to project into one of the column-like spaces of the frame longitudinally of such space and to exert pressure against the base members contained in said space, so as to prevent accidental displacement of the said base members, means resiliently acting upon each plunger whereby to render its pressure against the base members of the adjacent column-like space a resilient pressure facilitating the removal 90 and interchanging of said base members, and a part coöperative with each plunger to cause the same to exert a rigid non-resilient pressure against the base members with which it is adapted to coöperate. 95

In testimony whereof I affix my signature. 100
LOUIS OSTROW.
